UNITED STATES PATENT OFFICE.

MORTON HOMER MAGIE, OF LOS ANGELES, CALIFORNIA, ASSIGNOR OF ONE-HALF TO
CHARLES H. RUTH, OF HUNTINGTON PARK, CALIFORNIA.

TOOL-FEEDING MEANS FOR DRILLING RIGS.

Application filed November 14, 1921. Serial No. 514,940.

To all whom it may concern:

Be it known that I, MORTON HOMER MAGIE, a citizen of the United States, residing at Los Angeles, in the county of Los Angeles and State of California, have invented a new and useful Tool-Feeding Means for Drilling Rigs, of which the following is a specification.

This application is, in some respects a continuation of my application for a patent on a temper-screw, Serial No. 401,251, filed August 4th, 1920, and allowed May 16th, 1921; and involves improvements on said application in which the drilling line is operated by a chain driven worm-gear arrangement.

The invention relates to the mechanism used in well drilling rigs having a walking-beam for operating the tools.

In the art as heretofore practiced, the tool carrying end of the walking-beam when in position for operating the tools, has a perpendicular motion of from two to four feet; and when the engine end of such beam is down off of the crank pin, thus raising the working end of the beam, the up and down movement may be four or five feet, more or less, with lateral movement in the neighborhood of two feet, for withdrawing the temper-screw from over the hole, toward the Samson post to give clearance for other operations in the hole.

In present practice and in said application, the drilling clamps which carry the drilling line and tools are suspended by two links that are suspended from the two ends of a yoke or swivel that is connected to the bottom of the temper-screw, or the worm rack or bar shown in said application.

It is very difficult to construct such links of such exact lengths as to give a perpendicular pull on the line. As a result of this, the operation of the walking-beam at the lifting of the tools, produces a side whip or a throw of the line which frequently causes the line to strike the side of the casing, thus tending to wear both the line and the casing; and in addition to this creates a disagreeable vibration and a jerky operation which is injurious to the rig and drilling mechanism; and the resulting lateral strain sometimes causes breakage of the temper-screw.

In operating line tools, the driller is required to turn the temper-screw and to feed the tools into the hole as the hole is drilled; and this requires the use of a three decked stool commonly called the drilling, or knowledge bench, so that at the beginning of the operation, he can stand on the upper deck to turn the cross-bar of the temper screw, and as the drilling proceeds and said cross-bar lowers, the driller can take successively lower decks until he can operate from the floor.

When the temper-screw has thus been lowered, it is necessary to move it back up the line to the former starting position relative to the beam.

In order to do this the slack of the line is taken up by the bull-wheel, thus supporting the tools from the crown pulley; then the temper-screw is unclamped from the line and elevated to its former position; after which it is again clamped to the line, the bull-wheel released and the line above the clamp given the necessary slack; and then the work proceeds as before.

With present practice a heavy counterweight is employed to assist in returning the temper-screw to its elevated position; and said counterweight is attached to and has to be carried up and down by the walking-beam at each stroke. Such counterweight adds to the expense of the drilling rig and to the expense of installation; and also adds additional strain to the working parts and additional load to be carried by the walking-beam bearing and by the engine; and also when running the rig rapidly, it causes the temper-screw to jump from its bearings thus adding wear and danger of breakage; it also causes excessive vibration. It also interferes with the sensitive feeling that the driller needs to note in order to determine the exact conditions to be met at the bottom of the hole.

Furthermore the operation of lifting the temper-screw in the present practice requires the attendance of, and is difficult work for, two men.

An object of this invention is to provide means whereby the operation of the drilling rig will be more even and steady; will consume less energy of both engine and driller, and will reduce the time and effort of get-

ting the temper-screw back from the lower position to the starting position, and will also allow the temper-screw to be lowered rapidly to position for use in the operation 5 of jarring up for loosening tools or casing.

In present field practice the operation of jarring upward to loosen either tools or casing is attended by great difficulty and more or less danger of accident on account 10 of the heavy load necessary to be lifted in shifting the position of the jars; and an object of this invention is to make provision whereby the raising or lowering of the tools or jars can be accomplished practically by 15 one operator.

An object is to provide superior means for dispensing with the multiple deck stool necessary with the present practice.

The invention is broadly new, basic and 20 pioneer in that I use a worm rack for suspending, raising, and lowering the tools.

I have so constructed the appliance that the temper-screw for handling the tools is of an endless screw construction and acts on 25 a worm rack; and furthermore, in that provision is made for unshipping the worm and handling the worm rack by a pinion for rapidly raising and lowering the worm rack when the tools are suspended from the der- 30 rick.

An object is to avoid all danger of the weight of the tools causing the temper-screw to spin, and the tools to get away from the driller; and also to avoid the necessity of 35 alternately tightening and loosening the set screw heretofore provided to prevent such spinning of the temper-screw and falling of the tools.

Other objects, advantages, and features of 40 invention may appear from the accompanying drawings, the subjoined detail description, and the appended claims.

The accompanying drawings illustrate the invention.

45 Figure 1 is an elevation of my invention in a well rig, fragments of which are shown. The parts are in position with the worm rack up and supporting the tools, and in working position.

50 Fig. 2 is a view analogous to Fig. 1, showing the parts in working position with the worm rack down ready to be unclamped and run back to position shown in Fig. 1.

55 Fig. 3 is a view analogous to Figs. 1 and 2 showing the working beam unshipped or down and the temper-screw swung out of the way of the cable and the tools.

60 Fig. 4 is an elevation on a larger scale showing the invention viewed from beneath the walking beam, which is omitted from this view; the shaft that supports the reins being shown.

65 Fig. 5 is a broken side elevation on a larger scale than Figs. 1-4 showing a tem- per-screw constructed in accordance with

this invention, as suspended from the end of a walking-beam; and showing the hook attached to the rack-bar, and the shifting frame with its mechanism mounted on said bar.

70 Fig. 6 is a front elevation of what is shown in Fig. 5 with parts sectioned on line x^6 also showing the line and the clamp and bail.

Fig. 7 is a fragmental plan of the appliance viewed from the plane x^7 in Fig. 5, 75 omitting the housing of the endless chain.

Fig. 8 is broken, fragmental elevation viewed from line x^8 , Fig. 5, omitting the endless chain housing.

Fig. 9 is a plan view partly in section 80 with parts in position for raising or lowering while at work.

Fig. 10 is a view analogous to Fig. 9, with parts in position for rapid raising or lowering of the rack-bar to working position.

Fig. 11 shows how some of the teeth of certain members should be shaped to suit requirements.

90 In the drawings B indicates the bull-wheel; S the Samson post; W, the walking-beam; C, the crank; P the pitman; and D the derrick, all of which are of the usual construction.

R is a rack bar from which the line is sus- 95 pended.

The rack bar is supported by an endless screw or worm 1.

In carrying out this invention I construct 100 the temper-screw in the form of a rack sup- porting and operating worm 1, a worm rack 2 meshing therewith, reins 3 supporting the worm and journaled on a top bearing 4 which may be variously constructed and is shown in the drawings as a shaft upon which 105 a box 5 carried by the reins 3 is swung; and the worm is revolved by a worm gear 6, and its driving worm 7; said driving worm is mounted on a shaft 8 driven by a pulley or sprocket wheel 9 and endless chain 110 10 which depends nearly to the floor 11 upon which the workman stands to operate the temper-screw.

The worm rack forms a vertically mov- 115 able bail support and is provided at its lower end with a centrally arranged bail bearing 12 from which is hung a single bail 13 hav- ing a central bearing 14 to rest on said bail bearing; the top bearing at 4, 5, and the bail bearings being practically aligned ver- 120 tically. A suitable clamp 15 is provided to clamp the line 16 by which the tools, not shown, are suspended in the well 17.

For temper-screw operation the worm 125 rack 2 is suspended from the reins by means of engagement with the vertical operating worm 1 which is journaled in a frame 18 forming a bracket attached to the bottom of the reins 3.

130 A spur rack 19 is fixed to and extends

along the worm rack 2, and a pinion 20 therefor is fixed to the shaft 8, and the parts are so spaced that the rack bar R provided with the spur rack and the worm rack may 5 be operated alternately by the worm 1 and the pinion 20.

Provision is made whereby the worm rack 2 is horizontally shiftable relative to the frame 18. To this end the frame 18 is provided with transverse ways 21 for horizontal transversely shifting yokes 22, 23 which are arranged at the top and bottom of the frame 18 and are provided with vertical guides 24 for the worm rack.

15 Said yokes 22, 23 are connected together by the horizontal shifting screws 25, 26, the driven sprocket wheel 27, sprocket chain 28 and driving sprocket wheel 29, all operated by the crank 30.

20 Power applied by the crank 30 will simultaneously and equally slide both of the shifting yokes horizontally so that by turning the crank 30 the worm rack will be unshipped from the worm 1 and the spur rack 19 will 25 be meshed with the pinion 20.

The worm 1 and the pinion 19 are both operated by the endless chain 10 over sprocket wheel 9, and the endless chain is prevented from jumping off by the housing 31.

30 The worm 7 is revolved by the shaft 8 that is revolved by endless chain 10 to operate the worm gear 6 which revolves the worm 1.

35 When the worm 1 is in engagement with the worm rack, the operation of the chain will raise and lower the rack with power; and in drilling, the worm will support the tools at the predetermined depth relative to 40 the bearing 4, except when the chain 10 is operated to raise or lower the tools. When the chain is not being run the worm rack

2 is locked and will support the tools at a predetermined depth and the chain under 45 the operator's hand will give the operator the touch or feeling necessary to determine the condition of the work at the bottom of the hole, and the driller will move the chain 10 to lower the tools as the work proceeds.

50 When the tools are suspended by the line 16 from bull-wheel shaft 32 over crown pulley, not shown, as indicated in Fig. 3, the crank 30 can be operated to shift the yokes 22, 23 and the worm rack, into position to 55 mesh the spur rack 19 with the pinion 20; and then by operating the chain 10, the worm rack may be rapidly hoisted to the working position shown in Figs. 1 and 5.

When the worm rack is disengaged from 60 the worm, the chain, sprocket wheel and worm are free to run, and this might allow the rack bar R to drop down; to provide against such action, a spring operated thumb ratchet 33 is provided to engage the spur

rack 19 to prevent descent of the worm rack 65 and to allow easy ascent of the same when the pinion is operated for that purpose.

When it is desired to lower the worm rack, the thumb ratchet will be disengaged by the operator, and the chain operated to 70 lower said worm rack.

By the arrangement above described, whenever the tools are supported by the worm rack, the line hangs vertically and the thrust of the walking beam does not cause 75 the line to vibrate and whip the sides of the hole, and the operator has easy control of the tools. The sensitiveness of the endless chain 10 to the operation at the bottom of the hole is as complete for all practical purposes as with the ordinary temper-screw.

80 The operator can manipulate the tools while standing on the floor throughout all positions of the clamp 15.

85 The reins shown herein are equivalent to the forked shaped supporting member in the former application; said reins comprising two parallel fork members carried by the bearing which in turn is carried by the walking-beam; and lost motion is provided for 90 between the walking-beam and the rack bar in the present instance, by allowing the reins to move up and down with relation to the bearing 4 on the walking beam. The necessity of this lost motion arises from the fact 95 that when the weight of the line and tools is taken by the crown pulley and bull-wheel shaft at the time that the walking-beam is still operating; upward movement of the taut line relative to the beam, or downward 100 movement of the working end of the beam relative to the taut line will occur and will be accommodated by the lost motion means provided as shown between the bearing 4 and the reins.

105

I claim.

1. A temper-screw for well drilling machines comprising a fork-shaped supporting member, a rack bar slidably disposed in said supporting member, a screw engaging the 110 rack bar, a worm gear for operating the screw, and means for moving said screw into and out of engagement with said rack bar.

2. A temper-screw for well drilling machines comprising a fork-shaped supporting member, a vertical slidable rack bar disposed between the arms of said supporting member, a bracket carried by said supporting member, a screw journaled in said bracket and engaging said rack bar, a worm 115 gear for operating said screw, the shaft of the worm of such gear being prolonged, a pulley on said shaft and an endless chain carried by the pulley; and means for moving said screw into and out of engagement 120 with said rack bar.

3. A temper-screw for well drilling machines comprising a fork-shaped supporting

- member, a rack bar slidably disposed between the arms of said supporting member, a bracket connected to the arms of the supporting member, a screw journalled in said bracket and arranged to engage the rack bar, a worm gear for operating said screw, means, including an endless chain and a pulley, for operating said worm gear; a yoke carried by said fork-shaped supporting member, and means carried by the yoke for moving said screw into and out of engagement with said rack bar.
4. A temper-screw for well drilling machines comprising a fork-shaped supporting member, a rack bar slidably disposed between the arms of said supporting member, a bracket secured to the arms of the supporting member, a screw journalled in said bracket and arranged to engage the rack bar, a worm gear for operating said screw, means, including an endless chain and a pulley, for operating said worm gear, a yoke carried by said fork-shaped supporting member, and a shifting screw carried by the yoke for moving said screw into and out of engagement with said rack bar.
5. In a drilling rig; a worm rack for suspending, raising and lowering the tools; a worm and a pinion for operating said rack and means for unshipping the worm and moving the worm rack by the pinion for rapidly raising or lowering the worm rack.
6. A temper-screw having reins journalled on a top bearing and also having a vertically movable bail support provided at its lower end with a centrally arranged bail bearing; and a single bail having a central bearing to rest on said bail bearing; said bearings being practically alined vertically.
7. A temper-screw having reins journalled on a top bearing and also having a vertically movable rack bar bail support provided at its lower end with a centrally arranged bail bearing; a single bail having a central bearing resting on said bail bearing; said bearings being practically alined vertically; a worm-gear; a spur-gear; means for operating said worm-gear and said spur-gear, and means for causing the worm-gear and the spur-gear to operate the rack bar in alternation.
8. A temper-screw comprising in combination with a bail support, a rack-bar provided on one side with worm-gear teeth and on the other side with spur-gear teeth; a worm and a spur gear respectively arranged to be brought into common clearance with the respective worm and spur-gear teeth of the rack-bar; means for operating the worm and the spur-gear and means for relatively shifting the rack on the one part, and the worm and spur-gear on the other part, to cause operation of the rack by the worm and by the spur-gear alternately.
9. The combination with a rack-bar having worm-gear teeth on one side and spur-gear teeth on another side; of a worm adapted at one position relative to the rack-bar, to mesh with the worm-gear teeth of said bar; and at another position to be out of mesh therewith; a spur gear adapted to be in mesh with the spur-gear teeth of the rack-bar at a time when the worm-gear is out of mesh with the worm-gear teeth; a frame carrying the worm and the spur-gear and means to shift the frame for alternative operation of the rack by the worm and by the spur-gear.
10. The combination with a walking beam and a transverse shaft thereon; of reins journalled on said shaft; a frame fixed to and supported by said reins and provided with a vertical guideway; a rack-bar provided with worm-gear teeth and spur-gear teeth; a shaft mounted vertically on said frame and provided with worm gear teeth and with a worm, said worm being adapted to mesh with the worm-gear teeth of said rack; a shaft journalled horizontally on said frame and provided with a worm meshing with the worm-gear of the vertical shaft, and also provided with a spur-gear adapted to mesh with the spur-gear teeth of the rack-bar; means to shift the frame relative to the rack-bar to alternately mesh the vertical worm and the spur gear with the rack-bar; and means to revolve the horizontal shaft.
11. The combination with a walking-beam, of means for supporting a cable, and means carried by the walking-beam and adapted to operate said cable supporting means alternately with power and with speed.
12. In combination with a walking-beam and with means supporting a cable; of lost motion means connecting said cable supporting means with the walking-beam, and comprising means for raising and lowering the cable supporting means alternately with power and with speed.
13. The combination with a walking-beam of means for supporting a cable; and means carried by the walking-beam and adapted to operate said cable supporting means alternately with power and with speed; and means to prevent the cable supporting means from accidentally descending.
14. In a device of the character set forth a rack bar provided with a worm rack and with spur-rack; a worm and a pinion for alternately operating said rack bar by the worm rack and by the spur-rack and shifting means for unshipping the worm and meshing the pinion with the spur-rack.
15. Tool feeding means for well drilling rigs comprising a fork-shaped supporting member, a rack bar slidably disposed in

said supporting member; a screw engaging the rack bar and a worm rack for manipulating the screw.

16. The combination set forth of the reins, the worm rack adapted to support well drilling tools, and a worm carried by the reins and adapted to operate the worm rack.

In testimony whereof, I have hereunto set my hand at Los Angeles, California, this 8th day of November, 1921.

MORTON HOMER MAGIE.

Witness:

JAMES R. TOWNSEND.
